UNITED STATES PATENT OFFICE

EBEN RAY PACKER, OF NEW ROCHELLE, NEW YORK

SWITCH-POINT PROTECTOR

Application filed April 20, 1929. Serial No. 356,791.

This invention relates to improvements in switch point protectors for railway switches or turnouts and consists of improved features of construction and arrangement designed to be efficient in reducing wear and damage to switch points, to reduce derailments at switch points, to have adequate strength and to be particularly economical of manufacture to allow 10 of economy in the first cost of installation and in the replacement or renewal of the wearing surfaces.

The device of the present invention incorporates important features disclosed in 15 a prior patent to me under date of June 19, 1928, No. 1,674,178, and consists of further structural improvements embodied therein, specially adapted to obtain substantial economies in the cost of manufacture and 20 installation. A particular feature of the present type of switch point protector consists in the provision of a supporting member and an insert or bearing portion member formatively providing the wearing or 25 contact surfaces and which is desirably made of a manganese steel casting so as to afford a maximum degree of durability and resistance to wear. In the disclosure of my prior patent aforesaid, the supporting member 30 is of a design to have engagement with the fishing surfaces of the rail and has integrally formed therewith a laterally extended bracing structure operative to resist the very severe lateral thrust to which the 35 device for this purpose is subjected. As a result of the severe stresses imparted to the supporting member in actual use, it is desirable that the supporting member shall 40 be made of a steel relatively high in its physical properties and desirably made of a casting of a high grade electric furnace steel. As a result thereof, where the supporting member and its bracing structure 45 are integrally formed, it has been found that the cost of manufacture is relatively high both by reason of the required use of the higher grade steel and likewise the pattern expense incident to the casting of the 50 varied forms of bracing structures required

in connection with the variations in switch point tie plates commonly in use.

In accordance with the present invention I have formed the supporting member and the bracing structure therefor, as separable parts and of a form to effectively cooperate and to be readily assembled without the requirement of additional fastening devices. By so doing, I am enabled in the first instance to effect a substantial economy in 60 the employment of a reduced weight of the higher priced steel and, moreover, an additional economy incident to the reduction in pattern expense in that the arrangement allows of the employment of a single pattern for a given sized rail and which may be universally employed in conjunction with variations in the switch plates or tie plate construction, and wherein the bracing structure is formed of standard bar material 65 of a relatively lower grade steel but fully adequate for its purpose and which may be inexpensively cut and formed to meet the varied clearance conditions imposed by the normal variations in switch point plates 70 and tie plates and likewise special tie plate installations as they are met.

The foregoing and other features and advantages of my device will be understood by reference to the accompanying drawings 80 wherein like reference numerals are applied to the corresponding parts in the several features.

In the drawings:

Figure 1, is a vertical transverse sectional view of an improved switch point protector embodying the features of the 85 present invention.

Figure 2 is a plan view thereof.

Figure 3 is a view thereof in side elevation.

Figure 4 is a vertical transverse sectional view illustrating the desirable modification: and

Figure 5 is a plan view thereof.

The improved switch point protector, as shown in the drawings, comprises a deflector member "a" adapted to be positioned, as shown, upon the outer side of the main track rail 1, opposite to the extreme end or 100

reduced portion of the movable rail or switch point, as will be readily understood. The protector "a" consists of a supporting member 2 composed of an upper or head portion 3, a vertical web portion 4, having an inner flange extension 5, positioned to engage the upper fishing surface of the rail base flange and a bearing member or portion adapted to engage the car wheel. As here shown, upon the upper or head portion 3, there is removably mounted a separable insert or bearing member 6 having an upwardly extended longitudinal bearing portion or deflecting flange 7 positioned to have its inwardly directed surface engaged by the outer or non-flange surface of a car wheel for the purpose of inwardly deflecting the latter and for the latter purpose has its end portions angularly disposed or outwardly deflated as indicated at 8-8 in Figure 2. The separable insert member 6 is desirably of a manganese steel casting or of a high grade steel alloy having the property of high resistance to wear and is further of a form with relation to the supporting member whereby the pressures applied thereto from the car wheel will be transmitted to the supporting member by bolts or other securing means. For this purpose the head portion of the supporting member is formed with a seat to receive the bearing member 6, the seat being formed by the upper surface of the horizontal wall of the head portion in conjunction with an outer vertical flange portion 10 engaged by the outer vertical surface of the bearing member 6. The lateral or outward pressure imparted to the car wheel is accordingly resisted by the vertical flange portion 10 of the supporting member 4, and provision is likewise made for inter-engagement between the bearing member and the supporting member to resist relative longitudinal movement, i. e., movement in a direction longitudinal of the rail. To this end, the bearing member has integrally cast thereon, depending perforated lugs 12 fitted to slots or apertures in the horizontal wall of the supporting member. For securing the parts described in operating relation to the rail, the web portion of the support member is provided with bolt apertures 14 positioned to register with the apertures of the lugs 12 and securing bolts 15 are passed through said apertures and through a registering aperture in the rail and a securing nut 16 is threaded to the bolt whereby the bolt and nut will operate to secure both the supporting member and the bearing member in position, the arrangement at the same time providing inter-engagement between the bearing member and supporting member to resist relative longitudinal movement. The bearing member, as best shown in Figures 1 and 3, is formed at its inner lower edge

with an inwardly extending flange portion 18 engaging the rail head fishing surface.

A further important feature of the present invention provides for bracing of the deflector member, composed of the bearing and supporting members, against the severe lateral thrust so as to, to a substantial degree, relieve the securing bolts from the stresses thereof. In the improved arrangement, the bracing members are separately formed of commercial bar stock and are indicated at 20 angularly disposed with their outer end portions bent at 21 to bear upon the ties and perforated at 22 to receive the usual securing spikes. To co-operate therewith, the outer flange portions 10 of the supporting member at the intermediate and end portions of the device are provided with slots or recesses 23 to receive the upper end of the bracing members 20. Also, as best shown in Figure 2, the slots for receiving the bracing members at the respective ends of the structure are elongated with relation to the width of the bracing members, thereby allowing a desirable longitudinal adjustment of the end bracing members to accommodate for differences in spacing of the ties associated with the installation.

As will be appreciated, the improved feature of the separable bracing members allows of said members being made up of commercial bar stock, thereby to effect a substantial economy and further allows of effecting a direct bracing connection between the head portions of the supporting member and the tie in a manner to best provide clearance or noninterference with the switch tie plate, one type of which is here shown at 26. Moreover, as aforesaid, the use of the separable brace members results in a further economy in pattern costs, and likewise it facilitates installation by reason of the provision for adjustability of the end brace members to accommodate for varied tie-spacing at the different locations.

While I have disclosed an approved embodiment of the present invention, it will be understood that varied modifications may be made therein without departing from the scope of the appended claims. As illustrative thereof, I have shown in Figs. 5 and 6 a desirable modified form wherein the deflector member, composed of the supporting and bearing members is shown as a one piece casting and wherein the bracing member is formed of a separable piece of rolled bar steel and wherein it is bent back at its outer end and extended beneath the track rail thereby forming an integral tie plate portion 28. At its inner end, this tie plate portion, as shown, is apertured to receive a securing spike at 29 in position for engagement with the rail flange.

Having described my invention, I claim:

1. A switch point protector adapted for

use in combination with a main rail and a movable switch point operatively associated therewith and to be positioned for deflecting a car wheel in the direction of switching comprising a deflector member adapted to be secured with relation to the rail and formed with angularly disposed deflecting surfaces and with an outwardly directed seat or recess and a separable bracing member therefor fitted to the recess and inclined downwardly therefrom to the tie and said recess being elongated with relation to the width of the bracing member to allow of adjustably positioning of the bracing member with relation to the tie.

2. A switch point protector adapted for use in combination with a main rail and a movable switch point operatively associated therewith and to be positioned for deflecting a car wheel in the direction of switching comprising a deflector member adapted to be secured with relation to the rail and formed with angularly disposed deflecting surfaces and with outwardly directed recesses at its intermediate and end portions and separable bracing members formed of flat bar steel fitted to said recesses and downwardly inclined with their outer end portions bearing upon the ties and said recesses at the end portions being elongated to allow of adjustably positioning of the braces to accommodate for varied tie spacings.

3. A switch point protector adapted for use in combination with a main rail and a movable switch point operatively associated therewith and to be positioned for deflecting a car wheel in the direction of switching comprising a deflector member composed of a supporting member and a bearing member supported thereon and formed with angularly disposed deflecting surfaces, said supporting member being formed with recesses at its outer side and bracing members fitted to the recesses and inclined outwardly and downwardly for attachment to the tie and certain of said recesses being elongated to allow of adjusting the position of the bracing members with relation to the ties, said bracing members being formed of flat bar steel angled to have bearing on the tie and apertured for spiking thereto.

Signed at New York city, in the county of New York and State of New York, this 27th day of March, A. D. 1929.

EBEN RAY PACKER.
